ABSTRACT

A method for operating a hot blast stove characterized in that when intermittently operating a plurality of hot blast stoves each having a pressure supply valve, a cold blast valve, a stack valve, a hot blast valve and the like, the blast pressure within the hot blast stove at the time of transfer to the regeneration process after completion of the blast process is supplied by means of the pressure supply valves to another hot blast stove in which the "on blast" state is going to start after completion of regeneration, thereby effectively utilizing the residual pressure and heat.

1 Claim, 3 Drawing Figures

FIG. 1

FIG. 2

FIG. 3

METHOD FOR OPERATING HOT BLAST STOVE

The present invention relates to a method for operating a hot blast stove and in particular a method for intermittently operating a plural number of hot blast stoves.

The operation of a hot blast stove in case intermittent operation will be described hereinunder.

For generating hot air to supply to a blast furnace, a plural number of stoves are provided for each blast furnace. Each hot blast stove comprises a combustion chamber and a regeneration chamber, regenerative bricks being heated during the combustion process, cooling air being passed through the regenerative bricks during the blast process, whereby air heated by the regenerative bricks is supplied to the blast furnace.

According to a conventional method, either a small port of a cold blast valve, the first valve in the blasting system, or a pressure supply valve is opened in order to start the blast process after completion of the combustion process. A problem arising in this instance is the decline of blast pressure. That is, pressure control of the blower for supplying blast to the blast furnace and adjustment of the opening of the small port and the pressure supply valve is necessitated so as to prevent fall of pressure in the main blast pipe and the hot air supply pipe, respectively. However, the variation of the blast pressure and that of the amount of blast flow complicated curves not conforming to the predetermined conditions. Moreover, the switchover requires a considerably long period of time resulting in disadvantageous loss of efficiency in the operation of the blast furnace.

An objective of the present invention is to eliminate the aforementioned defects involved in the conventional method.

This and other objects are accomplished by the parts, improvement, combinations and arrangements comprising the present invention, a preferred embodiment of which is shown by way of examples in the annexed drawings and herein described in detail. Various modifications or changes in details of construction are comprehended within the scope of the appended claim.

FIG. 1 shows a schematic layout of four hot blast stoves for embodying the method of this invention.

FIG. 2 is a schedule showing the state of operation of each part of the foregoing.

FIG. 3 - I is a diagram of a schedule showing the relation between the blast and combustion in each stove.

FIG. 3 - II is a diagram showing the variation of pressure in each stove.

In FIGS. 1, 1HS, 2HS, 3HS and 4HS designate hot blast stoves respectively, a regeneration chamber 12 and a combustion chamber 13 being provided in each said stove. Numeral 11 designates a main blast pipe, 11 communicating with each regeneration chamber 12 of respective hot blast stove 1HS - 4HS through each cold blast valves CV₁ - CV₄. A cold blast branch pipe 18 is connected to an intermediate portion of a pipe connecting each regenerating chamber 12 of each blast stove 1HS - 4HS to each cold blast valve CV₁ - CV₄ through respective pressure supply valves PSV₁ - PSV₄, a primary pressure supply valve PSV₀ common to each stove being provided adjacent to the connection of the cooling air branch pipe 18 to the main pipe 11.

Numeral 14 designates a flue connected to a stack 19. The flue 14 communicates with each regeneration

chamber 12 of each of hot blast stove 1HS - 4HS through stack valves SVA₁, SVA₂, SVA₃, SVA₄ and SVB₁, SVB₂, SVB₃, SVB₄ respectively. Numeral 15 designates a hot blast main pipe, the hot blast main pipe

5 15 communicating with each combustion chamber 13 of respective hot blast stove 1HS - 4HS through each hot blast valves HV₁ - HV₄. Numeral 16 designates a combustion air pipe connected to each combustion chamber 13 of each hot blast stove 1HS - 4HS. Intermediately on each said pipe 16 is mounted an air shut off valve AV₁ to AV₄, respectively. Numeral 17 designates a gas pipe and in each said gas pipe 17 is mounted a gas shut-off valve BV₁ - BV₄ and a primary gas valve GV₁ - GV₄, respectively.

10 15 Referring now to FIG. 1, the first hot blast stove 1HS is in the state of "on gas" when the stack valves SVA₁, SVA₂ are opened and the air shut-off valve AV₁, the primary gas valve GV₁ and the gas shut-off valve BV₁ are opened. In this case, combustion gas enters through

20 20 the gas pipe 17, said combustion gas being mixed with air supplied through the air pipe 16 and burned within the combustion chamber 13 of hot blast stove 1HS, said combustion gas after heating the regenerative bricks within the regeneration chamber 12 by changing its course in the upper part of the combustion chamber 13 being discharged into the stack 19 through the flue 14. Next, the hot blast stove 1HS is in the state of "on

25 25 blast" when the cold blast valve CV₁ and the hot blast valve HV₁ are opened. Originally, when a single unit is "on blast," the primary pressure supply valve PSV₀ and the pressure supply valve PSV₁ are opened on conditions while all the valves for the stoves in the state of "on gas" are closed, cooled air from the cold blast main pipe 11 being supplied to the regeneration chamber 12 of the hot blast stove 1HS.

30 30 When the difference between the pressure within cold blast main pipe 11 and that within the regeneration chamber 12 of the hot blast stove 1HS reaches a predetermined value, the primary pressure supply valve PSV₀ and the pressure supply valve PSV₁ are closed, the blast valve CV₁ being opened, the hot blast valve HV₁ being opened, whereby hot air is supplied to the hot blast main pipe 15.

35 35 40 The temperature within the hot blast main pipe 15 is controlled by an independent controlling device (not shown).

45 45 The foregoing is the description in connection with the first hot blast stove 1HS, and the same is applicable to each of the other hot blast stoves 2HS - 4HS.

50 50 As described hereinbefore, each of the hot blast stoves 1HS - 4HS is operated intermittently, and more than one such stove are operated in the order as illustrated in FIG. 2.

55 55 The hot blast stoves 1HS - 4HS are set in the state as indicated hereinunder.

60	4HS	on blast
	3HS	on blast
	2HS	on gas
	1HS	on gas

65 65 FIG. 2 shows the state of switchover when a blast signal is given to the hot blast stove 3HS when the state of operation of each hot blast stove is as described above.

First, a signal (a) is given to the hot blast stove 1HS and 3HS thereby causing alarm bells STX₁, STX₃ to ring. Then the primary gas valve GV₁ of the hot blast stove 1HS starts to close, the blast valve CV₃ of the hot blast stove 3HS starts to close, the cold blast valve CV₁, and the hot blast valve HV₃ being completely closed.

The hot blast stove 3HS waits for a next instruction in the state as described hereinbefore.

In the hot blast stove 1HS, the primary gas valve GV₁ is completely closed, the gas shut-off valve BV₁ is then closed, the air shut-off valve AV₁ is then closed, and the stack valves SVA₁, SVB₁ are then closed, whereby the process from on gas to repose is completed. Then in the hot blast stove 1HS the process is switched over from repose to on blast, the hot blast stove 3HS switches the process from repose to on gas, the alarm bell STX₁, STX₃ ringing, the pressure supply valves PSV₃ and PSV₁ being opened, whereby the blast pressure within the hot blast stove 3HS is supplied to the cold blast branch pipe 18 through pressure supply valve PSV₃. The blast pressure supplied to the branch pipe 18 enters the hot blast stove 1HS through the pressure supply valve PSV₁.

The pressure supply valves PSV₁ and PSV₃ are maintained in an open state until the time limit predetermined by a timer TM₁, the blast pressure within the hot blast stove 3HS being supplied to the hot blast stove 1HS during the lapse of time predetermined by said timer TM₁.

The supply of pressure is supervised by the blast pressure (not shown) of each stove, approximately one half of the pressure being transferred to the hot blast stove 1HS. Therefore, the time limit predetermined by the timer TM₁ is computed by an electronic data processing system so as to make it possible to supply one half of the pressure as described hereinbefore.

Thus, after the lapse of time predetermined by the timer TM₁, the pressure supply valve PSV₃ is closed, and the primary pressure supply valve PSV₀ is opened, whereby insufficient blast pressure is supplied to the hot blast stove 1HS from the blast main pipe 11 through the primary pressure supply valve PSV₀, the cooling air branch pipe 18 and the pressure supply valve PSV₁. This pressure supply is effected exclusively within the time limit predetermined by the timer TM₁.

The hot blast stove 3HS, with the completion of the first-stage work, is transferred to the state of on gas. The remaining blast pressure is discharged into the flue 14 through the stack valve SVA₃. This discharge is effected exclusively within the time limit predetermined by the timer TB₃, a succeeding process starting thereafter.

The supply and discharge of pressure are effected by making use of the timers TM₁, TM₃, TS₁, TB₁, TB₃ provided on the hot blast stoves 1HS and 3HS, respectively. However, the operation is carried on similarly also in case of other methods, for example, a combination of a pressure difference detector a, pressure measuring device and an electronic computing system. In the first hot blast stove 1HS during the process leading up to "on blast," the pressure supply valves PSV₁ and PSV₀ after the lapse of the time limit predetermined by the timer TS₁ are closed, the cold blast valve CV₁ being completely opened synchronously with the cleaning signal, and then the hot blast valve HV₁ being opened, whereby the first hot blast stove is placed in a

state parallel with the hot blast stove 4HS already in the state of on blast.

In the hot blast stove 3HS, the stack valves SVA₃ and SVB₃ are completely opened simultaneously with the termination of the blasting, and the air shut-off valve AV₃, gas shut-off valve BV₃, and gas valve GV₃ are opened, whereby transfer to the on gas state is completed and regeneration is commenced. For the foregoing processes, the stoves respectively are selected automatically by a program set by a relay or an electronic data processing system, the opening and closing of each valve also being adapted to be automatically conducted in a predetermined order.

Now the switchover of the stoves and the variation of pressure will be explained hereinunder in reference to FIG. 3.

FIG. 3 shows the state of operation of the same stove as illustrated in FIG. 2, i.e., the hot blast stoves 3HS and 4HS are in the state of on blast, the hot stoves 1HS and 2HS being in the state of "on gas" in FIG. 3 - I, the parallel line on the upper side of each horizontal line 10 showing each stove indicates the state of on blast, the parallel line on the lower side indicating the state of on gas, the oblique line indicating transfer to either on gas or on blast respectively. In FIG. 3 - II showing pressure within the stove, the oblique line indicates either a rise or a fall of pressure, the parallel lines indicating the state in which on blast is being supplied with an accumulation of predetermined pressure.

30 In FIG. 3, the hot blast stove 1HS is transferred from the state of on gas to repose by the signal(a). When the hot blast stove 3HS is in the state of repose, the hot blast stove 1HS starts into the on blast state, the pressure within the hot blast stove 1HS commencing to rise 35 from the point A simultaneously with the pressure within the hot blast stove 3HS commencing to fall until it becomes substantially same as that of the hot blast stove 1HS, as indicated at the point B.

When the process has proceeded to the point B, the 40 hot blast stove commences a preliminary action for the next process, the pressure within the stove becoming same as the atmosphere.

In the hot blast stove 1HS, transfer to the on blast 45 process is continued, said transfer and transfer to the combustion process in the hot blast stove 3HS being completed at the point C.

Subsequently, the state of on blast continues in the hot blast stove 1HS, the state of combustion being continued in the hot blast stove 3HS. For signals (b), (c), (d), the same process is conducted though the order of the hot blast stoves varies. The embodiment comprises four units of hot blast stoves, but the switchover process is same for more than four units of hot blast stoves excepting for an increase in the number of signals.

50 As described hereinbefore, the hot blast stove of this invention is characterized in that pressure is supplied to the stove on the occasion of transfer to the on blast from the on gas process after a repose, the pressure within the hot blast pipe being free from any effect even during the supply of pressure. Since the pressure is supplied by making use of the residual pressure of the on blast state from another hot blast stove, the heat efficiency is better in the present invention than in case of the conventional method in which cool air is blown into the stove. And, when transfer to the "on gas" is effected after completion of blast, the blast pressure of the stove is reduced by half to resulting in the shorten-

ing of discharge time thereby making it possible to protect the smoke duct. Moreover, the present invention makes it possible to dispense with the use of a program setting device, timer, electronic data processing system and the like at the time of commencing blast for the blast stove required in case of the conventional method thereby making it possible to stabilize the operation due to the flexibility of this invention a, which makes it adaptable to whatever system that may require a change.

What is claimed is:

1. A method of operating a system of hot blast stoves for a blast furnace which system is made up of a plurality of hot blast stoves each having a cold blast valve, a pressure supply valve, a flue valve and a hot blast valve, the system further having a cold blast main pipe to which the cold blast valves of all of the stoves are connected, a cold blast branch pipe branching from said cold blast main pipe with a branch pipe pressure supply valve therebetween and to which all of the pressure supply valves are connected, a stack to which all of the flue valves are connected, and a hot blast pipe to which all of the hot blast valves are connected, said method comprising supplying combustion fuel to at least one of the stoves for heating it in an on blast operation while 25

keeping the cold blast valve, pressure supply valve and hot blast valve to the one stove closed and leaving the flue valve open, while at the same time operating at least one other stove in an on regeneration operation by 5 keeping the cold blast valve and the hot blast valve open and the flue valve and the pressure supply valve closed, thereby to pass cold gas through the said other stove to heat it, and then switching over the operation of the one stove to an on regeneration operation and the other stove to an on blast operation by first closing 10 the cold blast valve and the hot blast valve of said other stove, and opening the pressure supply valve thereof while closing the branch pipe pressure supply valve, and at the same time closing the flue valve and ending the fuel supply to the other stove and opening only the pressure supply valve thereof for admitting the hot gas from the other stove to the one stove through the cold blast branch pipe, and thereafter closing the pressure supply valve of the said other stove and opening the flue valve thereof and starting supply of fuel thereto, while closing the pressure supply valve of the one stove 15 opening the cold blast valve and the hot blast valve thereof.
